UNITED STATES PATENT OFFICE.

ULRIC HÉBERT, OF BLACK RIVER, CANADA.

COFFIN-HANDLE.

SPECIFICATION forming part of Letters Patent No. 651,437, dated June 12, 1900.

Application filed February 9, 1900. Serial No. 4,617. (No model.)

To all whom it may concern:

Be it known that I, ULRIC HÉBERT, a subject of Her Majesty the Queen of Great Britain, residing at Black River, county of Arthabaska, Province of Quebec, Canada, have invented certain new and useful Improvements in Coffin-Handles; and I do hereby declare that the following is a full, clear, and exact description of the invention, such as will enable others skilled in the art to which it appertains to make and use the same.

This invention relates to handles for coffins; and one object is to provide a removable coffin-handle which can be quickly and easily attached to and detached from the coffin and which can be readily adjusted to fit any-sized coffin.

A further object is to provide a coffin-handle which is simple in construction, effective in operation, and can be manufactured at a moderate cost.

To these ends the invention consists in a removable and adjustable coffin-handle constructed substantially as hereinafter illustrated and described, and defined in the appended claims.

Referring to the drawings, in which similar letters of reference indicate similar parts, Figure 1 is a view in elevation of a coffin-handle constructed in accordance with this invention. Fig. 2 is a side view thereof, showing in dotted lines the position assumed by the parts when in their closed position. Fig. 3 is a central vertical section on line 3 3 of Fig. 1.

In the drawings, A represents a coffin-handle, which may be of any preferred shape or material and suitably ornamented, as desired. Upon the body portion of the handle are secured two outwardly-extending arms a, on the lower part of each of which are formed the downwardly-depending lugs a' a''. In suitable bearings formed in the lugs a' is journaled the cross-bar a³, having a groove a⁴ formed centrally on its side, which is wide at its inner portion, forming a guideway. On the side of the cross-bar a³ opposite the groove a⁴ is secured a lug a⁵, having in its upper end a removable pin a⁶. Pivottally connected to each of the lugs a² is a link a⁷, in each of which is formed a series of perforations a⁸. Pivottally connected to the links a⁷ by means of pins a⁹ are the links b, which are pivottally con-

nected to a cross-piece B, to each end of which is secured a hook b'. Centrally arranged in the cross-piece B is a shallow groove b², in which is adapted to slide the vertically-adjustable gripping-bar B', the body portion of which is engaged by and slides in the guideway a⁴ of the cross-bar a³ and is provided with perforations b³, with any one of which the pin a⁶ is adapted to engage and lock the bar B' in its adjusted position. Secured to the upper side of the cross-piece B is the guide-rod B², which lies upon and slides against the front face of the bar B' and is guided in the groove a⁴ and held against the bar B' by means of the strap b⁴.

The adjacent faces of the gripping-bar B' and the hooks b' are provided with suitable pins b⁵, which prevent the parts from accidentally slipping off the coffin.

The parts having been adjusted by means of the pins and perforations to fit the coffin with which the handles are to be used, the handle A is placed in its lowered position, (see Fig. 2,) when the gripping parts are separated to their fullest extent. The hooks and gripping-bar B' are then fitted over the edges of the coffin and the handle raised to its highest position, whereupon the coffin will be tightly clamped and cannot become disengaged without first lowering the handle.

While I have herein shown a preferred form of carrying my invention into effect, yet I do not desire to limit myself to such preferred details of construction, but claim the right to use any and all modifications thereof which will serve to carry into effect the objects to be attained by this invention in so far as such modifications and changes may fall within the spirit and scope of my said invention.

I claim—

1. A handle for coffins, comprising a handle having outwardly-extending arms; a cross-bar journaled in said arms; a gripping-bar slidably mounted in said cross-bar and adapted to be locked in its adjusted position; a cross-piece adjustably connected with said arms; and gripping-hooks formed at each end of the said cross-piece, substantially as described.

2. A handle for coffins, comprising a handle having outwardly-extending arms; an outer

and an inner lug fixed upon each of said arms; a cross-bar journaled in the said outer lugs; and having a grooved guideway formed therein; a gripping-bar slidably mounted in said 5 guideway and having perforations therein; a lug carried by said cross-bar and having a locking-pin adapted to engage said perforations, whereby the gripping-bar is locked in its adjusted position; a cross-piece adjustably connected to said inner lugs by means 10 of links; gripping-hooks secured at each end

of the said cross-piece; and a guide-rod centrally secured to said cross-piece and adapted to lie upon and slide along the said gripping-bar, substantially as described.

In witness whereof I have hereunto set my hand in the presence of two witnesses.

ULRIC HÉBERT.
